Filed Feb. 22, 1972, Ser. No. 228,477

Term of patent 14 years

Int. Cl. D9—03

U.S. Cl. D9—224

FIG. 1 is a perspective view of a combined razor blade dispenser and date indicator showing my new design looking in the direction of the top, front, and right side thereof;

FIG. 2 is a perspective view thereof looking in the direction of the bottom, front, and right side thereof;

FIG. 3 is a top plan view thereof;

FIG. 4 is a front elevation view thereof;

FIG. 5 is a left side elevation view thereof;

FIG. 6 is a top plan view of an alternate embodiment thereof; and

FIG. 7 is a left side elevation view of the alternate embodiment of FIG. 6.

The bottom, front, and right side of the alternate em-

bodiment shown in FIGS. 6 and 7 are identical to that shown in FIG. 2.

I claim:

The ornamental design for a combined razor blade dispenser and date indicator, as shown and described.
